UNITED STATES PATENT OFFICE.

SILAS H. WILSON, OF AUBURN, NEW YORK.

MACHINE FOR TWISTING SPIKES.

SPECIFICATION forming part of Letters Patent No. 227,084, dated April 27, 1880.

Application filed October 3, 1879.

To all whom it may concern:

Be it known that I, SILAS H. WILSON, of Auburn, in the county of Cayuga and State of New York, have invented a new and useful Improvement in Machines for Twisting Spikes, of which the following is a specification.

The object of my invention is to provide a machine for giving to railway and other spikes a uniform twist from the head to the point.

The invention comprehends an improved combination of rotary jaws, reciprocating die-wheels, and feeding mechanism.

The invention consists, secondly, of grooved rollers journaled in a carriage which is adapted to move toward and from the rotary jaws, which receive the spike, carry it to the jaws, and hold it against rotating while the jaws are twisting it, the lower grooved roll having also a vertical movement to allow the spike to pass between it and the upper roll, and to enable it to release the spike after the twist is put in it.

The invention consists, thirdly, of a plunger for forcing the spike from the feeding-trough between the grooved rolls.

The invention consists, lastly, of the devices and arrangements for producing the several movements, which will be specifically described in connection with the parts they operate.

In the accompanying drawings, Figure 1 is a top view or plan of my improved spike-twisting machine. Fig. 2 is a vertical longitudinal section of the same on line $x-x$ of Fig. 1. Fig. 3 is a vertical cross-section on line $y-y$ of Fig. 1. Fig. 4 is a front view of the jaws and the head in which they are held. Fig. 5 is a sectional side view of the jaws and the head, taken on line $z-z$ of Fig. 4. Fig. 6 represents a front-end view of the plunger for operating the jaws, and Fig. 7 represents a twisted spike.

Similar letters of reference indicate corresponding parts.

Referring to the drawings, A is the frame of the machine, supported on legs B. On top of the frame, at the rear end, is journaled transversely a shaft, a, carrying on one end a balance-wheel, b, and on the opposite end a fast pulley, c, and loose pulley c'.

d d are pinions fixed to shaft a on both sides of the frame A. Said pinions mesh with spur-

wheels e e on shaft f, placed transversely of frame A in bearings in pillow-blocks f' f'.

C C are parallel guide-rods, supported at one end in transverse bearing-block D and at the opposite end in transverse bearing-block D'.

E is a sliding frame, having a transverse horizontal slot, g, through which the shaft f is passed. At the forward end, h, of this frame are right-angular arms h' h', with sockets through them for the reception of the ends i i of guide-rods C C, said ends projecting back through bearing-block D and serving as guides and supports for the forward end, h, of the sliding frame E. The rear end of frame E is provided with a bar, i', which projects through a slot, i'', in standard E', rising from the rear end of frame A. Standard E' and ends i i of guide-rods C support frame E and allow it a free reciprocating motion. Between sides j j of frame E a cam, F, is fixed to shaft f, and at the front and rear of said cam are friction-rollers l l' on axes journaled in the sides j j, so that when the cam is revolved by the shaft f it strikes one of the rollers—say l—and moves frame E back, and when said cam reaches the opposite side of shaft f from roller l (if the frame E has not been drawn forward by an arrangement that will be fully described hereinafter) it strikes roller l' and forces frame E forward. In this way, by means of cam F, a sliding reciprocating motion is given to frame E.

G is the rotary head which carries the jaws for clasping and twisting the spike. Said head is provided with a hollow shaft or gudgeon, m, which has its bearing in the block D. Shaft or gudgeon m is held in its bearing by a collar, n, fixed to the rear end, n', which projects back through block D. On the periphery of the collar n is a spur-gearing, o, which meshes with a pinion, o', fixed to shaft p, held in bearings p' p'. Said shaft p carries at its rear end a beveled gear-wheel, p'', which meshes with a beveled pinion, p''', fixed to shaft a, so that when shaft a is rotated it communicates rotary motion through shaft p to the shaft or gudgeon m and head G.

H is a plunger-shaft passed through hollow shaft m. The rear end, q, of shaft H is pivoted in the end h of frame E, and said end q is

held in connection with frame E by screw-collars $q' q'$, which prevent the end q from drawing out of the hole in end h , but at the same time allow it to rotate freely, so that when frame E is reciprocated it slides shaft H back and forth in the shaft m , for a purpose that will be presently described.

The shaft H projects from the shaft m into the socket r of head G, and within socket r are four wings, $r' r' r' r'$, radiating from shaft H at right angles to each other. (See Fig. 6.) Head G is provided with four radial slots, $s s s s$, at right angles to each other, which extend from the socket r through the walls of the 15 said head.

The jaws are designated by the letter t . They extend outside of head G, but have extensions t' , which are placed in the slots s and held there by pivots t'' in the manner clearly 20 shown in Fig. 5. The outer edges, u , of extensions t' are curved to form segments of true circles. On curved edge u are placed flat springs u' , the outer ends whereof are fixed to the extensions t' , while the free ends u'' bear 25 against the curved walls u''' of the slots s . The action of the springs u' is to keep the jaws t open, as shown in Fig. 5.

The rear ends of extensions t' are formed into downwardly-curved fingers v , and on the 30 inside edges of said extensions are formed fingers v' . When the shaft H is placed in shaft m and head G the wings r' are held adjacent to the inside edges of extensions t' , between fingers $v v'$, so that by moving shaft H out or 35 forward the forward ends of wings r' strike fingers v' , and by turning the extensions t' on their pivots open the jaws t ; but when said shaft is drawn back the inclined back edges of wings r' strike fingers v , throw the 40 rear end of the extensions t' up, and close the jaws t .

This opening and closing of the jaws can be produced by the cam F, reciprocating frame E, and plunger-shaft H; but as it is necessary 45 that the jaws should be opened more quickly than the frame E is moved by the cam F, the springs u' are provided to open said jaws. When the springs u' throw the rear ends of the extensions t' down, the fingers v , striking against 50 the wings r' , throw the shaft H and frame E forward before the cam F reaches the friction-roller l' ; but in case of a failure of the springs u' to act, or the jaws t should stick from any cause, the cam F, striking roller l' , will force 55 the frame E and shaft H forward, and the wings r' , striking the fingers v' , will force the jaws t open.

The mechanism for carrying the spikes to the jaws and holding them while being twisted 60 consists of a carriage, I, placed in the space between the two sides of frame A. Said carriage has two arms, $I' I'$, extending up at either end through horizontal holes v'' , wherein are passed the guide-rods C C, so that the said 65 carriage will slide freely back and forth on said guide-rods. From the upper ends of arms I' project horizontally short shafts, v''' , with

pivots v'''' projecting from the ends. On these pivots v'''' are held the forward ends of connecting-rods J J. The opposite ends of said rods J J are pivoted to crank-pins $w w$ on spur-wheels e . By the rotation of spur-wheels e a reciprocating motion is communicated through connecting-rods J to carriage I. From the under side of carriage I depend two rods, $w' w'$. To the lower ends of rods w' is screwed 70 a plate, I'' , carrying at each end friction-rollers w'' , which bear against the under edge of rail J' , which is held at each end in hangers K K, depending from the under side of frame A. The upper edge of rail J' is V-shaped, and is divided into two parts, $x x'$, connected by an incline, y , the part x' being higher than part x .

The friction-rollers w'' , bearing against the 85 under edge of rail J' , steadies the movements of the carriage I and prevents said carriage from lifting, and thus relieves the guide-rods C C from strain.

L is a U-shaped frame placed on carriage I 90 in an inverted position, and secured thereto in any suitable manner. In the sides $a' a'$ of frame L are vertical transverse slots a''' .

M is a plate having on its edges flanges $b' b'$ and in its lower end a recess, c' . Plate M is 95 placed between sides $a' a'$ of frame L with its flanges b' in slots a''' . Plate M' is attached to the upper end of plate M, and is connected by means of set-screws $d' d'$ with the arms $d'' d''$ of frame L. By means of screws $d' d'$ plate 100 M can be set higher or lower in frame L. In recess c' of plate M is pivoted a V-grooved wheel, e' .

N is a plate placed in frame L below plate M. Plate N has flanges on its edges, which 105 project into slots a''' , and a recess, c'' , in which is pivoted a V-grooved wheel, e'' , immediately under and in line with wheel e' . Plate N is held in a vertical position in a mortise, e''' , in frame L and carriage I, and in its lower end is a V-grooved roller, f'' , which rests on the V-edge of rail J' , so as to run freely back and forth thereon. A vertical movement is given to 110 plate N for the purpose of opening and closing the wheels $e' e''$, which I call the "holding-die wheels," their office being to hold the spike against turning while the twist is being given to it by the revolving jaws t . It is necessary that these die-wheels $e' e''$ shall open to allow the head of the spike to pass through 115 and then close on the shank of the spike, and this opening and closing is brought about by the movement of plate N, which is produced in the following manner: Plate N is held in a 120 vertical position in mortise e''' , but is not fastened, so that it can move with perfect freedom up and down; but it is supported by its V-roller f'' , resting on the V-edge of rail J' , which, as before mentioned, is divided into two parts, $x x'$, connected by an incline, y . When roller 125 f'' is on the higher part, x' , the die-wheel e'' is held up to the die-wheel e' ; but when roller f'' is on the lower part, x , die-wheel e'' is lowered 130 away from die-wheel e' , leaving sufficient space

for the head of the spike to pass between said die-wheels $e' e''$. Therefore when the machine is in motion and the carriage is being reciprocated to and from the revolving jaws t , and it moves away from the jaws in the direction of arrow 1, the roller f'' , passing down the incline y to lower part, x , of rail J' , lowers die-wheel e'' , so that the head of the spike (which is at that moment fed out by the feeding mechanism) passes between said die-wheels. The carriage then moves toward the jaws t , and the wheel f'' , passing up the incline y , closes the die-wheels $e' e''$, which clasp the shank of the spike in the **V**-grooves in their peripheries and carry the spike to the revolving jaws t . The head of the spike passes between jaws t , which at that moment are closed down upon it. At the same moment when the jaws clasp the head the carriage commences to move back in the direction of arrow 1, the **V**-wheels $e' e''$ roll along the shank of the spike, but hold it firmly against turning, and the revolving jaws t twist the shank of the spike from the head thereof toward die-wheels $e' e''$, the twist following immediately behind the wheels $e' e''$ as they move back. By the backward movement of the holding-die wheels $e' e''$ from the jaws t an even twist is given to the shank, extending its whole length, and forming a spiral shank such as that shown in Fig. 7. The distance traveled by carriage I from the jaws t for the wheel f'' to reach the incline y should equal the length of the shank of the spike, so that when the wheel f'' passes down the incline y and the die-wheels $e' e''$ are opened the end of the shank will have passed out of said die-wheels, and, as the jaws t open at the same moment, the spike is thereby released and it drops to the floor, while another spike is fed between die-wheels $e' e''$, and the operation proceeds as before.

The feeding mechanism consists of a **V**-shaped trough, O , behind carriage I, and in line with die-wheels $e' e''$. Said trough is supported by a cross-head, P , which slides on guide-rods C . The rear end of the trough is formed into a cylinder, P' , which projects through a guide-hole, g' , in bearing-block D' . A slot, g'' , in the upper side of the cylinder receives the end of a pin, g''' , which prevents the cylinder and trough from being thrown forward too far by the spiral springs g'''' , wrapped around the guide-rods C , between the bearings of cross-head P and the block D' , the office of said springs g'''' being to throw the trough O toward carriage I.

Q is a triangular plunger placed in trough O , where it is held by a guard, h'' , placed over the top of the trough. Plunger Q is provided with arms h''' , and from these arms a shank, h'''' , extends back through cylinder P' . The end of said plunger projecting through the end of the cylinder is provided with a nut, i'' , to prevent the plunger from being drawn out from the trough. Shank h'''' is wrapped with a spiral spring, j'' , one end whereof bears against

the plunger and the other end bears against the end of cylinder P' , as shown in Fig. 2.

The plunger is operated by the movement of the carriage I in the following manner: 70 To a shaft, k' , journaled in frame A transversely under trough O , are attached two levers $R R'$, the upper forked ends, $l'' l'''$, whereof are on opposite sides of the trough O , and in the forks l'' is placed arm h''' , as clearly shown 75 in Fig. 1. Lever R extends below shaft k' , and its lower end, m' , is pivoted to one end of a horizontal rod, m'' . The rod m'' is passed loosely through a hole in ear n'' , projecting from one of the rods w' . (See Fig. 3.) On the 80 end of rod m'' , beyond the ear n'' , is a nut, m''' .

The operation of this part of the invention is as follows: When the carriage I moves back in the direction of arrow 1 its arms I' , coming in contact with the cross-head P , force the cross-head and trough O back, the springs g'''' readily allowing the cross-head to move back. When the carriage moves toward the jaws t the springs g'''' force the cross-head P and trough after it until the pin g''' reaches the 90 end of slot g'' and stops the forward movement of the said trough and cross-head. As the carriage advances toward the jaws to carry the spike last fed to the die-wheels $e' e''$ the ear n'' , coming in contact with the nut m''' on 95 rod m'' , turns the levers $R R'$ in the direction of arrow 3, and these levers move the plunger Q back in the trough O , so that when the carriage I reaches the end of l'' its movement toward the jaws t the plunger is sufficiently far 100 back in the trough to allow space for a spike in the trough O . The spike is placed in the trough by the operator with its head toward the carriage, and the carriage, moving back from the jaws t , relieves the levers $R R'$ from 105 strain, and the spring j'' , acting on the plunger, forces it forward toward the approaching carriage I, and as the die-wheels $e' e''$ open the plunger forces the spike out of the trough, the head passes between die-wheels $e' e''$, and as the 110 carriage at this point commences to move back the die-wheels $e' e''$ close up and carry the spike just received to jaws t , as before described.

This machine is specially adapted to twist 115 spikes while cold; but it can be used equally well to twist them while hot.

Having thus described my invention, I claim as new and desire to secure by Letters Patent—

1. In machines for twisting spikes, the combination of the rotary head G , carrying jaws t , the reciprocating carriage I, provided with holding-die wheels $e' e''$, and the feeding mechanism, the latter being arranged to co-operate 125 with the carriage and holding-dies, as shown and described.

2. The jaws t , pivoted in slots s in head g , and provided with fingers $v v'$, in combination with head G , shaft m , springs w' , plunger-shaft H , provided with wings r' , frame E , and cam F , all constructed and operating in the man-

ner and for the purpose substantially as hereinbefore described.

3. In combination with the reciprocating carriage I, holding-die wheels $e' e''$, and vertically-adjustable plate N, the track J', provided with the two parts $x x'$ and incline y , substantially as and for the purpose described, whereby, as the carriage is reciprocated, the lower holding-die wheel, e'' , is alternately lowered and raised, for the purpose specified.

4. In combination with the reciprocating carriage I and holding-die wheels $e' e''$, the feeding mechanism herein described, consisting in the trough O in cross-head P, and plunger Q in trough O, arranged and operat-

ing in the manner substantially as hereinbefore described.

5. In combination with the plunger Q, held in trough O and provided with a shank, h''' , and arms h'' , the spiral spring j'' on shank h''' , levers R R', fulcrumed on shaft k' , rod m'' , passed through ear n'' and provided with a nut, m''' , and reciprocating carriage I, substantially as and for the purpose hereinbefore described and set forth.

SILAS H. WILSON.
